METHYL CRESYL OR XYLYL S- α ARAKYL DITHIOPHOSPHATES

Fred K. Kawahara, Park Forest, Ill., and Russell H. Brown, Munster, Ind., assignors to Standard Oil Company, Chicago, Ill., a corporation of Indiana
No Drawing. Original application Nov. 17, 1961, Ser. No. 153,201. Divided and this application Dec. 8, 1964, Ser. No. 424,159

3 Claims. (Cl. 260—964)

This is a division of application Ser. No. 153,201, filed No. 17, 1961 now abandoned.

This invention relates to motor fuels characterized by their ability to suppress surface ignition in the operation of internal combustion engines. More particularly, the invention provides an improved motor fuel which is effective in suppressing surface ignition or "preignition."

Current emphasis on high compression ratios and other high-performance design features in gasoline engines of the internal combustion type has created a situation where random knock from surface ignition, often referred to as "preignition," has become a limiting factor in engine design and operation. Knock induced by surface ignition appears to be a result of the use of organo lead compounds, particularly tetraethyl lead, as the anti-knock agent in high octane number fuels. When leaded motor fuels are burned in internal combustion engines, deposits of carbonaceous material and lead salts are continuously formed on the combustion chamber walls. Apparently surface ignition, that is, the ignition of the fuel-air mixture either before or after passage of the spark, is caused by glowing of carbon in the deposits. It is generally believed that the presence of lead compounds in the deposits causes the carbon to glow at a significantly lower temperature than the glow point of carbon alone.

It is well known that the addition of certain organic compounds of phosphorus, such as tricresylphosphate, to leaded fuels results in reducing surface ignition. Unfortunately, phosphorus compounds vary widely in effectiveness, and those that are most effective often have the undesirable properties of lowering the octane number of the fuel as well as increasing the octane requirement of the engine. With petroleum refiners spending millions of dollars annually to raise the octane numbers of premium motor fuels, any substantial decrease in octane number is of course intolerable. And, by the same token, the refiner cannot provide a fuel that will itself aggravate the octane problem.

In accordance with the invention, an additive for use with leaded motor fuels has not been discovered which is extremely effective in reducing surface ignition or "preignition," yet when employed in proper quantities, does not substantially reduce the octane number of the fuel or increase the octane number requirement ("ORI") of the engine. Specifically, it has now been discovered that certain thioesters or dithiophosphoric acid, herein sometimes referred to as the methyl cresyl and methyl xylyl S- α -phenylethyl dithiophosphate, having the formula

2

wherein "n" is 1 or 2 and X is a mononuclear aralkyl radical having from 7 to about 15 carbon atoms, are outstanding preignition suppressant additives when incorporated into leaded gasolines in an amount sufficient to provide a mol ratio of phosphorus to lead of from about 0.01 to about 1.0. Preferably, the molar ratio of phosphorus to lead (MR P/Pb) is in the range of 0.02–0.30.

It has further been discovered, contrary to experience with many other organic compounds of phosphorus, that the inventive additives do not reduce oxidation stability of the gasoline, and hence do not increase the tendency of the motor fuel to form gums in storage. In addition, they do not cause fuel induction system deposits nor they cause sticking of engine intake and exhaust valves.

15 The motor fuel of the invention may contain tetraethyl lead equivalent to a concentration of from about 0.5 ml. to about 5 ml. or more per gallon of the hydrocarbon motor fuel; the concentration of tetraethyl lead may be varied as is usual with the engine and its use.

20 The hydrocarbon component which constitutes the base of the fuel will preferably be gasoline but may be any other combustible liquid of suitable volatility commonly employed as fuel for internal combustion spark ignition engines, including paraffinic, naphthenic and aromatic

25 hydrocarbons, pure hydrocarbons such as isooctane, and mixtures of isooctane with other suitable liquid hydrocarbons. These fuels may be derived, in whole or in part, by distillation of crude oil, catalytic or thermal cracking of gas oils, alkylation of isoparaffins with olefins, polymeriza-

30 tion of olefins, etc. The boiling point of such fuels should be in the range of about 80° F. to about 500° F. and preferably in the range of about 90° F. to about 420° F. Motor fuels may also contain anti-oxidants, stabilizers, dyes, anti-icing agents, halogen-type lead scavenging

35 agents and/or other compounds which are commonly employed in leaded motor fuels.

There can also be provided, in accordance with the invention, an additive concentrate suitable for incorporation into leaded motor fuels which contains a substantial

40 amount (1–100%) of the above described thioester of disubstituted thiophosphoric acid. Thioester concentrations of 5–85 wt. percent are preferred. The additive concentrate may also contain an inert solvent, such as a refined hydrocarbon oil, and also desirable amounts of tetraethyl lead (to provide an MR P/Pb in the range of 0.01–1.0), halo-hydrocarbon lead scavenging agents, dyes, and the like.

The defined additives may be prepared by any of the conventional means known for preparing analogous thioesters. Thus, substantially equimolar mixtures of methanol and a cresol or xylol may be reacted with phosphorus pentasulfide (P_2S_5) to form a dithiophosphoric acid, and then reacted with an olefin of the radical (X) to be introduced. It will be appreciated that amounts of

50 other materials, e.g. the dimethyl or the dicresyl compounds will be formed, but these also appear to be excellent additive constituents. Typical examples of appropriate cresols include p-cresol and commercial m-cresol and p-cresol mixtures, as well as o-cresol. Commercial xylene is also quite satisfactory.

55

60 It is preferred, for reasons of convenience and economy, to react the dithiophosphoric acid with an olefinic hydrocarbon having up to 15 carbon atoms per molecule to form the inventive additive. As previously mentioned, the X group is aralkyl, and accordingly the olefinic hydrocarbon can be any compound which affords such group.

65 Among the suitable compounds which can form the X

group of the defined formula are styrene, α -methyl styrene, dimethyl- α -methyl styrene, p-t-butyl styrene, and other aralkenes of 8-15 (more desirably 8-10) carbon atoms. Using the styrenes, it is believed that the sulfur atom attaches to the α carbon atom of the styrene.

As specific embodiments of the invention, the following examples are given. It is to be understood that these are by way of illustration only and are not intended as a limitation of the invention:

Example I

This example illustrates the manner of preparing the inventive additives. For the preparation of methyl xylyl-S- α -phenylethyl dithiophosphate, the following ingredients are used:

Ingredient	Wt. g.	Moles
(1) Methanol.....	39	1.2
(2) Commercial xylene.....	146	1.2
(3) Phosphorus pentasulfide.....	111	0.5
(4) Styrene.....	124	1.2
(5) Solvent-extracted SAE-SW motor oil.....	88	-----

All of the methanol, xylene, and motor oil are placed in a flask and heated to 160-180° F. Phosphorus pentasulfide is slowly added in increments of several grams at a time over a one-hour period. The temperature is then increased to 210° F. to permit the xylene and P_2S_5 to react; this temperature is maintained for one-half hour. Then, at 210° F., all of the styrene is added dropwise, and the temperature thereafter increased to 220-230° F. and held there for two hours. Upon cooling, a solution is obtained which contains approximately 6.4 wt. percent phosphorus.

Example II

The preparation of methyl p-cresyl S- α -phenylethyl dithiophosphate, the procedure of Example I is followed, except that 1.2 moles of p-cresyl alcohol is substituted for the xylene.

Example III

In a manner similar to that of Example I, but with a commercial mixture of p-cresyl alcohol and m-cresyl alcohol replacing the xylene on a 1:1 molar basis, is carried out the preparation of methyl m-p-cresyl S- α phenylethyl dithiophosphate.

Various phosphorus additives were tested in an engine operated to determine surface ignition suppression effectiveness. This engine is a single cylinder, CFR-L head engine, having a 7 to 1 compression ratio. Typical operating conditions for surface ignition or "preignition" studies are as follows:

Test duration, hours 50
Coolant temperature, ° F. 148
Oil temperature, ° F. 160
Air to fuel ratio 13/1

For this test the engine is cycled as follows:

CYCLE CONDITIONS

Time, sec.....	45	135
R.p.m.....	600	900
Load.....	None	Full

Surface ignition prevention effectiveness was determined using a premium fuel having 3 cc. of TEL per gallon (in the form of commercial "motor mix," and including scavengers) and incorporated therewith the inventive additive and other phosphorus compounds.

EFFECTIVENESS IN SUPPRESSING SURFACE IGNITION
CFR-L HEAD ENGINE

5	Additive	Concentration, MR P/Pb		
		0.067	0.13	0.26
10	Methyl p-cresyl phenylethyl dithiophosphate.....	Percent 70	Percent 72, 89	Percent 92
	Methyl m-p-cresyl phenylethyl dithiophosphate.....		88	94
	Methyl xylyl phenylethyl dithiophosphate.....	65	88, 89	94-95
	(Dimethyl xylyl phosphate).....	43	54	91
	(Tricresyl phosphate).....	38	50	67

15 The test data in the above table demonstrate the superiority of the present additive over other phosphorus compounds with respect to surface ignition control. It will be noted that the additive may be employed at one-half to one-fourth the concentration of hitherto well known preignition suppressants.

20 It was previously indicated that a major advantage of the inventive additive is in its ability to be incorporated into high octane gasolines without substantially reducing the octane number of said gasolines. To demonstrate this, tests were made in a CFR-L head engine at various concentrations of various concentrations of several additives in a 97-99 octane number motor fuel, containing 3.0 cc. TEL per gallon. The following results were observed.

OCTANE NUMBER DEGRADATION

30	Additive	Concentration, MR P/Pb		
		0.13	0.26	0.33
35	Methyl p-cresyl phenylethyl dithiophosphate.....	-0.10	-----	-----
	Methyl m-p-cresyl phenylethyl dithiophosphate.....	-0.18	-----	1.00
	(Diisopropyl dithiophosphoric acid).....			

40 A surprising benefit attendant with many of the present additives is the absence of pro-oxidant effects which would lead to oxidative gum formation in the gasoline on long term storage. This was demonstrated by testing motor fuels at accelerated storage conditions of 212° F. and 100 p.s.i.g. oxygen pressure, and noting the time (induction period) before rapid oxygen consumption occurred. The following results were observed.

INDUCTION PERIOD

50	Additive	Concentration, MR P/Pb			
		0	0.13	0.26	0.33
55	Methyl p-cresyl phenylethyl dithiophosphate.....	640	440	-----	445
	Methyl m-p-cresyl phenylethyl dithiophosphate.....	800	860	900	-----

60 The additives were also tested for equilibrium octane performance in a 1953 Oldsmobile V-8 engine having special 10:1 compression ratio heads, under the following conditions:

Speed, r.p.m. 1500
Load, BHP 9.5
Coolant temp., ° F. 175
Oil temp., ° F. 165
65 Air-intake temp., ° F. 100
Air-intake temp., ° F. 100
Spark advance, ° BTDC 11

70 Once each hour the engine was operated at full-throttle, 1500 r.p.m.-80 BHP for 15 seconds. The equilibrium octane requirements and octane requirement increase (ORI) of the engine were determined after 150 hours of operation and are shown below. Superiority of the inventive compounds over their adjacent homologue, phenyl methyl S- α -phenyl ethyl thiophosphate is particularly noted.

OCTANE REQUIREMENT INCREASE

Additive	Conc., MR P/Pb	150-Hour Octane Rqmt.			Power Loss, percent
		Start	End	ORI	
None					
Methyl p-cresyl phenylethyl dithiophosphate	0.13	101	115.5	14.5	6.5
Methyl m-p-cresyl phenylethyl dithiophosphate	0.13	100	105	5	6.5
Methyl m-p-cresyl phenylethyl dithiophosphate	0.13	100	106.0	6.0	6.5
Methyl xylol phenylethyl dithiophosphate	0.13	100	104.5	4.5	3.5
(Methyl phenyl phenylethyl dithiophosphate)	0.13	100	105.5	5.5	3.6
			*114	14	3.6

*144 Hours.

The additives of Examples II and III were exposed to 15 the copper strip test, which consists of placing a clean copper strip in a sample of motor fuel containing the additive at 122° F., and examining the strip after three hours. At concentrations of 0.13 and 0.33 MR P/Pb, the strips had the same good color as the blank (zero additive concentration).

The additives also exert a powerful action on maintaining spark plugs in clean, unfouled condition. In tests on an Oldsmobile engine, the following results were observed:

SPARK PLUG LIFE					
Additive	Conc., MR P/Pb	Hours Before Fouling			
		Set A	Set B		
None		50	24		
Methyl p-cresyl phenylethyl dithiophosphate	0.13	>150	>150		
Methyl m-p-cresyl phenylethyl dithiophosphate	0.13	96,63	75		
Methyl xylol phenylethyl dithiophosphate	0.13	70	-----		

As shown in the table below, the inventive additives pass the air jet gum test of ASTM D-381, with respect to total gum formation. Not more than 4.0 mg. of gum is permissible in a satisfactory motor fuel.

AIR JET GUM, MG.

20	Additive	Concentration, MR P/Pb			
		0	0.13	0.26	0.33
	Methyl p-cresyl phenylethyl dithiophosphate	2.1	2.5	-----	3.5
	Methyl m-p-cresyl phenylethyl dithiophosphate	0.4	1.0	1.6	-----
	Methyl xylol phenylethyl dithiophosphate	3.5	-----	-----	-----

The percentages given herein and in the appended claims are weight percentages unless otherwise noted.

While the invention has been described by reference to specific embodiments thereof, the same are given by way of illustration. Modifications and variations will be apparent to those skilled in the art.

We claim:

1. Methyl cresyl and methyl xylol S- α aralkyl dithiophosphates.
2. Methyl cresyl S- α phenylethyl dithiophosphate.
3. Methyl xylol S- α phenylethyl dithiophosphate.
